UNITED STATES PATENT OFFICE.

THOMAS R. THOMPSON, OF WEST HAVEN, CONNECTICUT.

TOY.

Application filed March 18, 1923. Serial No. 95,528.

I do hereby declare the following, when taken in connection with the accompanying drawings and the characters of reference marked thereon, to be a full, clear and exact description of the invention, and which said drawings constitute part of this application, and represent, in—

Fig. 1 a perspective view of a toy constructed in accordance with my invention.

Fig. 2 a plan view with the top removed.

Fig. 3 an end view with the end-piece removed.

Fig. 4 a sectional view on the line 4—4 of Fig. 2.

Fig. 5 a perspective view of one of the slides detached.

This invention relates to improvement in toys, and particularly to toys having moving figures but which may also include sound-producing devices. The object of the invention is to produce a simple and attractive toy in which a series of figures will be projected above the upper face of the top and may embody a moving figure in front of the device, and the invention consists in the construction as hereinafter described and particularly recited in the claims.

In carrying out my invention, I employ a box-like casing 10 of any desired design and formed in its top with a longitudinal slot 11. In the front 12 of the box I form a vertical slot 13. In the inner face of the front 12 are a series of vertically-arranged guides 14, between which are slides 15 having heads or other devices. These slides are formed with holes or notches 17, and preferably above the holes or notches are blocks 18. Extending transversely through the box and supported by the ends thereof is a shaft 19, provided at one end with a crank-handle 20. Mounted in this shaft are a series of pins 21 arranged at different angles, one pin arranged in line with each slide and of a length adapted to engage with and raise the slides as the shaft is turned. To apply a friction or drag upon the shaft, I employ flat springs 22, which are secured in the case and extend into frictional engagement with the shaft 19 and, if desired, short pins 26 may be mounted in the shaft 19 in line with these springs, so as to depress their outer ends and allow them to snap back against the shaft to produce a sound. If desired, a bell 23 or other sound producing device may

be attached to the shaft, so as to turn therewith.

A figure 24 is mounted on a pin 25 extending through the slot 13 into one of the slides 15 and in line therewith, so that when this particular slide moves, the figure outside the box will move with it. As the shaft is turned, the pins will engage with the slides, in line with them, and lift the slides so as to expose the upper ends or heads through the slot 11, above the top of the box, and as the pins pass out of engagement with the slides they will drop by gravity. The object of providing the blocks 18 is to increase the time in which the head will be exposed.

This toy is simple in construction and amusing to watch, as the heads are successively exposed to view.

I claim:

1. A toy, comprising a box-like casing formed with a slot in its top, the inner face of the front of the box provided with guideways, toy-figures mounted in said guideways, a shaft extending through the box parallel with the front and in rear of the figures and provided with radial pins adapted to directly engage with and raise said figures at each revolution of the shaft.

2. A toy, comprising a box-like casing formed with a slot in its top, the inner face of the front of the box provided with guideways, toy-figures mounted in said guideways in line with said slot, notches in the back of said figures, a shaft mounted in said casing parallel with the front thereof and provided with pins arranged in line with said figures and adapted to engage with the notches thereof, whereby the figures are raised.

3. A toy, comprising a box-like casing formed with a slot in its top, the inner face of the front of the box provided with guideways, toy-figures mounted in said guideways in line with said slot, notches in said figures, blocks on the backs of said figures above said notches, a transverse shaft mounted in said casing and provided with pins arranged in line with and adapted to engage with the said notches, whereby the figures are raised.

4. A toy, comprising a box-like casing formed with a slot in its top, the inner face of the front of the box provided with guideways, toy-figures mounted in said guideways in line with said slot, a shaft extending

through the box parallel with the face thereof and provided with pins adapted to engage and raise said figures, and retarding springs extending into frictional engagement with said shaft.

5. A toy, comprising a box-like casing formed with a slot in its top, the inner face of the front of the box provided with guideways, toy-figures mounted in said guideways in line with said slot, a shaft extending through the box parallel with the face thereof and provided with pins adapted to engage and raise said figures, springs extending into frictional engagement with said shaft, and short pins mounted in the shaft and adapted to depress said springs.

6. A toy, comprising a casing, a transverse slot in the top of said casing, the front of the casing provided on its inner face with vertical guideways, vertically-movable toy-figures between said guideways in line with said slot, the front also formed with a vertical slot, a shaft mounted in said casing parallel with the face thereof, pins mounted in said shaft and adapted to engage and lift 25 said figures, and a figure mounted outside said figures, and a figure mounted outside the front face upon a pin extending through the vertical slot in the face into engagement with a toy-figure in line therewith.

In testimony whereof, I have signed this 30 specification.

THOMAS R. THOMPSON.
